UNITED STATES PATENT OFFICE.

JOSHUA B. BARNES, OF FORT WAYNE, INDIANA.

SPIKE.

SPECIFICATION forming part of Letters Patent No. 250,187, dated November 29, 1881.

Application filed April 18, 1881. (No model.)

To all whom it may concern:

Be it known that I, JOSHUA B. BARNES, a citizen of the United States, residing at Fort Wayne, in the county of Allen and State of Indiana, have invented certain new and useful Improvements in Railroad-Spikes; and I do hereby declare the following to be a full, clear, and exact description of the invention, such as will enable others skilled in the art to 10 which it appertains to make and use the same, reference being had to the accompanying drawings, and to the letters or figures of reference marked thereon, which form a part of this specification.

15 My invention relates to improvements in railroad-spikes; and the objects of my improvements are, first, to provide a spike of such width or with such an amount of bearing-surface upon the material into which it is driven 20 as to prevent the lateral movements of the engine and train, when running upon the track, from forcing the spikes outward or away from the rails, and at the same time provide for giving to the widened portion sufficient strength 25 to prevent it from being bent by the lateral action of the rolling-stock; and, second, to provide a novel construction of that part of the spike to which the claw-bar is applied for withdrawing the same from the cross-tie or other 30 timber in which it may be placed. I accomplish these objects by constructing spikes substantially in the form shown in the accompanying drawings, in which—

Figure I is a perspective view, showing the 35 head adapted for reaching over and resting upon the rail and the projecting lips formed thereon for the reception of the claws of the withdrawing-bar, the widened surface for bearing against the wood and preventing its movement laterally therein, a strengthening-rib 40 upon the outer surface of the widened portion to prevent such portion from being bent, and for supporting and strengthening the head, and also the method of beveling the lower portion of the spike for the purpose of facilitating 45 its entrance into the substance into which it is to be driven. Fig. II is an elevation, showing the outer or rear side of the spike, its head, the strengthening-rib, its widened portion, and 50 its beveled point; and Fig. III is a side elevation, showing the parts above enumerated and

how the strengthening-rib is made to support the outer portion of the head.

Similar letters refer to similar parts in the several figures.

Heretofore railroad-spikes have usually been made of square or round iron, and have had their heads formed mainly or wholly upon one side of their bodies, they being beveled upon this part, such construction affording no adequate means for the application of the claw-bar for withdrawing them from the ties, or of preventing them from being bent outward or away from the rails by the lateral action of the rolling-stock thereon.

I am aware that it is not novel, broadly, to provide a strengthening-rib upon the outer surface of a spike, such a device being shown in a patent granted to Theodore R. Timby, December 21, 1875, and numbered 171,447. I do 70 not therefore claim, broadly, a strengthening-rib upon a spike for railroads or for other purposes.

I am also aware that a patent was granted to Howard Greer on the 28th of December, 1880, No. 236,020, which shows, and in which is claimed, a spike having strengthening-ribs on both its outer and inner surfaces. This I do not claim.

In constructing spikes with my improvements embodied therein, I provide for the body A a part the width of which is greater than its thickness, its width being five (more or less) times greater than its thickness. The portion A may be of any required length, and has its 85 lower end beveled upon the sides composing its greatest width.

Upon the outer side of the portion A there is formed a strengthening-rib, B, which is of such width and thickness as to prevent the 90 body A from being bent outward in use, and is extended downward to such an extent as to cause the bevel formed upon its outer edge, when of the same degree of angularity as are those formed on the part A, to form a continuation of said angle upon that side of the spike upon which the rib is placed, thus giving to the spike the required amount of strength throughout its entire length with the least possible amount of metal.

Upon the upper ends of the parts A and B the head C is formed, it being substantially of the

form shown in the drawings, whereby it is provided with a projecting portion, C', for resting upon the rail, and also with laterally-projecting lips C² and C³, which are beveled or rounded 5 upon their under surfaces, for the purpose of adapting them to the reception of the claws of the bar used for withdrawing them from the substance into which they may be driven. The outer portion of the head C extends to the outer 10 edge of the strengthening-rib B, and thus prevents the lips from having their form changed by the driving of the spike.

My improved spike differs from that of Timby, above alluded to, and from all others with 15 which I am acquainted, in that it provides a largely-increased surface to rest against the substance into which it is driven, for the purpose of preventing it from being forced away from the rails of the track by the passing over 20 them of the rolling-stock; second, in the fact that adequate means are provided for the withdrawal of the spike by the formation of lips on the outer portions of its head; and, lastly, in that its body A is located near the center

of its head, and is united therewith, and with 25 a strengthening-rib on its outer surface, as a consequence of which the liability of breaking the head by drawing the spike is obviated.

Having thus described my invention, what I claim, and desire to secure by Letters Patent, 30 is—

A railroad-spike consisting of a flat bar of metal, A, of the requisite length and width, said bar being strengthened by the application to its outer surface only of the projecting 35 portion B, and having upon its upper end a head, C, which is formed upon both the bar A and portion B in such a manner as to leave upon each side of the strengthening portion B projecting lips C² C³, under which to place the 40 claws of a withdrawing-bar, substantially as described.

In testimony whereof I affix my signature in presence of two witnesses.

JOSHUA B. BARNES.
